UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed August 2, 1929. Serial No. 382,935.

This invention relates to car roofs of the pressed-steel type wherein the margins of the metal roof sheets are shaped and riveted together to form hollow seams that function 5 as carlines.

One of the principal objects of the present invention is to devise means for increasing the strength and rigidity of the hollow roof seams and for suspending an insulating lining 10 therefrom. Another object is to provide for detachably securing the seam strengthening and stiffening means within the hollow seams. Other objects are simplicity and cheapness of 15 construction and compactness of design.

The invention consists principally in stiffening and strengthening the hollow seams or 20 ribs of the roof by means of wooden fillers; it also consists in suspending an insulating lining from said fillers; it also consists in detachably securing said fillers within the 25 seams independently of the securing rivets therefor; and it also consists in the parts and arrangements and combinations of parts hereinafter described and claimed.

In the accompanying drawings, which 30 form part of this specification and wherein like symbols refer to like parts wherever they occur,

Fig. 1 is a plan view of a portion of a car 35 roof embodying my invention,

Fig. 2 is an enlarged transverse section through one-half of the roof, the section being taken longitudinally of one of the roof 40 seams on the line 2—2 in Fig. 1.

Fig. 3 is an enlarged fragmentary longitudinal section through the seam at one of the 45 bolt holder clips,

Fig. 4 is an enlarged transverse cross-section through the seam on the line 4—4 in 50 Fig. 3,

Fig. 5 is a similar section through the seam at the ridge on the line 5—5 in Fig. 2,

Fig. 6 is a plan view of a modified form 55 of built-up filler,

Fig. 7 is a side view thereof; and

Fig. 8 is a side view of another modified 60 form of filler.

Referring to the accompanying drawings, my invention is shown in connection with a 65 pressed-steel car roof of the type shown in

my patent, No. 1,330,975, dated February 17, 1920. Said car roof comprises Z-bar side plates 1 arranged with their webs vertical and with their top flanges projecting inwardly. The metal roof sheets 2 are arranged cross-wise of the car, extending from eaves to eaves with their eaves ends supported on and secured by rivets 3 to the outstanding flanges of eaves stiffening angles 4 whose depending flanges are riveted or otherwise rigidly secured flatwise to the outer faces of the webs of the side plates 1.

The roof sheets 2 slope downwardly from the ridge to the eaves where they are turned down over the eaves angles 4 to form drip flanges 5. The roof sheets are provided along their adjacent side margins with hollow upstanding ribs 6 that fit one over the other and have flat tops that are rigidly secured together flatwise by rows of rivets 6a, thereby forming raised hollow seams, which function as roof supporting carlines as well as weatherproofing joints. As shown in the drawings, the hollow roof seams or ribs diminish in depth toward the eaves of the car where they are curved downwardly and merge into the body of the sheets adjacent to the drip flanges 5 at the eaves ends thereof.

Running boards 7 extend longitudinally of the car at the ridge and are preferably supported on and rigidly secured to the top flanges of Z-shaped running board saddles 8 whose bottom flanges are supported on and rigidly secured to the flat tops of the roof 80 seams by the securing rivets 6a therefor.

Located within each hollow seam of the roof is a wooden filler strip 9 which extends substantially from end to end of said seam and thus serves as a stiffener to increase the strength and rigidity thereof. Said stiffener also serves as a means for attaching an insulating lining 10 to the underside of the roof. The insulating lining 10 is preferably secured to the bottom of each filler by means of 85 nails 11.

The fillers 9 are detachably secured within the hollow ribs or seams of the roof by means of carriage bolts 12 that are suspended from straps or clips 13 located inside said ribs or 90 seams and secured to the top walls thereof by 100

the securing rivets 6 therefor. These bolt holder clips 13 preferably comprise metal straps that extend lengthwise of the seams adjacent to the ridge and eaves with their 5 ends riveted flatwise to the underside of said seams. The straps are perforated intermediate their ends to receive the bolts 12, and have their perforated portions offset downwardly, as at 13a, to accommodate the heads of said 10 bolts. The upper surfaces of the fillers 9 are notched or gained, as at 14, cross-wise to accommodate the bolt holders and also have bolt holes extending therethrough from top to bottom thereof that are enlarged at their 15 lower ends to accommodate the nuts 15 for the bolts.

In the modification shown in Figs. 6 and 7, the filler 9a is made in two pieces that are disposed in abutting relation at the ridge and 20 are connected together so as to act after the manner of a beam by means of a metal plate 16 that fits in slots in the adjacent ends of the two pieces and is secured thereto by bolts 17.

In the modification shown in Fig. 8, the 25 filler 9b is made in two pieces that are not connected at the ridge line but merely abut at this point and thus operate to strengthen the roof seam through the compression of their abutting surfaces.

30 By the arrangement described, the fillers serve to strengthen and stiffen the hollow seams and thereby increase the load capacity at the roof. The fillers also serve as nailing strips for the insulating lining which can be 35 quickly and easily applied to the roof; and they may be quickly and easily mounted in the hollow seams and readily removed and replaced without disturbing or loosening the securing rivets therefor.

40 What I claim is:

1. A car roof comprising roof sheets extending from side to side of the car and having their side marginal portions shaped and riveted directly together to function as hollow carlines, filler members for said carlines, and means for detachably securing said filler members in said carlines, said means comprising members permanently secured to said 45 seams by the securing rivets for the cooperating side marginal portions of said roof sheets and members supported by said permanently secured members and detachably engaging said filler members.

50 2. A car roof comprising roof sheets extending from side to side of the car and having their side marginal portions formed into hollow ribs that are lapped and rigidly secured directly together at their tops to form hollow seams, filler members for said seams, and means for detachably securing said filler members in said seams without disturbing the securing means for said hollow ribs.

55 3. A car roof comprising roof sheets extending from side to side of the car and having their side marginal portions formed into

hollow ribs that are lapped and rigidly secured together to form seams, filler members for said seams, means for detachably securing said filler members in said seams without disturbing the securing means for said hollow ribs, and an insulating lining located beneath said roof and secured to said filler members. 70

4. A car roof comprising roof sheets having hollow ribs therein extending from side 75 to side of the car, filler members for said ribs, and means for detachably securing said filler members in said ribs, said means comprising straps permanently secured to the tops of said ribs, and bolts supported by said straps. 80

5. A car roof comprising roof sheets extending from side to side of the car and having their side marginal portions shaped and riveted together to form hollow seams, filler members for said seams, and means for detachably securing said filler members in said 85 seams, said means comprising bolt holders permanently secured in said seams by the securing rivets therefor, and bolts carried by 90 said bolt holders.

6. A car roof comprising roof sheets extending from side to side of the car and having their side marginal portions shaped and riveted together to form hollow seams, filler members for said seams, and means for detachably securing said filler members in said 95 seams, said means comprising metal straps disposed in said seams with their ends permanently secured to the top walls thereof and having the portion intermediate their 100 ends perforated and offset downwardly, and bolts extending through the perforations of said straps with their heads supported on the downwardly offset portion thereof.

7. A car roof comprising roof sheets extending from side to side of the car and having their side marginal portions shaped and riveted together to form hollow seams, fillers for said seams, each of said fillers comprising two wooden strips disposed one on 105 each side of the ridge, a metal plate overlapping the adjacent ridge ends of said strips, bolts for securing said plate to said strips, straps located in said seams with their ends secured thereto by the securing rivets therefor, and bolts depending from said straps and engaging said filler strips. 110

Signed at New Kensington, Pennsylvania, this 30th day of July 1929.

CHARLES DAVID BONSALL. 120
